UNITED STATES PATENT OFFICE.

GEORGE D. PEARSON, OF MONTREAL, QUEBEC, CANADA, ASSIGNOR OF ONE-HALF TO GEORGE EDWARD DRUMMOND, TRUSTEE, AND ROBERT COWANS, BOTH OF SAME PLACE.

CAR-COUPING.

SPECIFICATION forming part of Letters Patent No. 377,770, dated February 14, 1888.

Application filed December 17, 1887. Serial No. 258,929. (No model.)

To all whom it may concern:

Be it known that I, GEORGE DECARIE PEARSON, a subject of the Queen of Great Britain, and a resident of the city of Montreal, in the 5 District of Montreal and Province of Quebec, Canada, have invented new and useful Improvements in Car-Couplers; and I do hereby declare that the following is a full, clear, and exact description of the same.

10 The present invention has reference to further improvements in my previous invention in car-couplers for which Letters Patent of the United States were granted on the 15th day of December, A. D. 1885, No. 332,430, to so arrange the coupler therein set forth that an ordinary link and pins may be used in combination therewith for further securing the cars together, and such improvements as may be hereinafter set forth.

15 20 The particular combinations of parts which form my present invention will be hereinafter set forth and claimed.

In the drawings hereunto annexed similar letters of reference indicate like parts, and 25 these will also be made, as far as convenient, to agree with the letters of reference used in the specification of the hereinbefore-mentioned patent.

Figure 1 is a side elevation embodying my 30 present invention. Fig. 2 is a plan of the invention shown in Fig. 1. Fig. 3 is a vertical section taken on line x x , Fig. 2. Fig. 4 is a modification of my invention shown in section, also as taken at line x , Fig. 2. Fig. 5 is an 35 illustration of how one of my improved couplers may be used in connection with many of the forms of bunters at present in use. Fig. 6 is a detail of construction.

Letter A is a portion of the body of a car, 40 B the end of frame, C the "dead-head," and D the strap or gland, all arranged as described in my said former patent.

In this specification the back of the bunter is the end which extends under the car. Therefore, when any part or thing is spoken of as 45 being at the back of another, it will be understood that it is relatively so placed. The front of the bunter is the extreme end of the bunter which projects out beyond the car, and when

any part or thing is spoken of as being in front 50 of any other part or thing it will be understood to be relatively so placed.

E are the bodies of the bunters, (sliding in the straps D,) provided at their front ends with extensions F, as shown in Figs. 1 and 2, 55 having open spaces G and H, pivot bolts or pins K, and pawls L, constructed and arranged as in my said previously-patented invention, excepting the following changes, hereinafter mentioned:

Instead of the pins I described in my said previous patent, I in my present invention form bridge-pieces I', integral with the ends of the extensions F, upon which the pawls L hook in a similar manner that they are described to hook on the pins I in my said previously-patented invention when both said pins I are in place.

In this present invention I extend the extensions F downward (see Figs. 1, 3, and 4) an 70 amount required for forming a suitable space, M, for a link, N, and a second bridge-piece, I'. In the modification shown in Fig. 4 three bridge-pieces, I', are provided, forming two spaces, M, for the link N to be placed in, and 75 thus, if the cars are of very unequal heights, provide for the same. Through the bridge-pieces I' holes O are formed for the reception of pins P, and, furthermore, in the top bridge-piece I' a counterbore, R, is provided of suitable size for the heads of the pins P to be received in, (see Figs. 3 and 4,) so that the said heads may not form any obstruction to either of the pawls L coming to the position shown at 80 85 3, Fig. 3.

In my present invention eyes may be formed on the upper sides of the pawls L for lifting them by, as shown and described in my said previous patent.

By providing the bridge-pieces I', space M, 90 pins P, link N, extensions F to the bunter's bodies E, in the form shown and described, they form an important improvement of the present invention independent of the combination of these said parts with the pawls L. 95 This I will now describe.

From the relative position of the body of the bunter E and that of the space M two

bunters of two cars can be brought together, after which the link may be introduced from the back of the space M, as shown by the position of the link I, and placed in the position 5 2, (see Fig. 5,) the position 2 being also the position the link is shown in in Figs. 2 and 3. By this arrangement the cars may be coupled with an ordinary link and pins, the novelty in this case consisting in the particular arrangement of the parts by which (the ends of two bunters of two cars being brought together, and while the cars are stationary in such said position) the link N may be placed in position from the back of the space M, after 10 which the pins P may be put in place. The above also enables one of my improved bunters to be engaged in a similar manner with many of the ordinary forms of bunters at present in use, as illustrated in Fig. 5, where A' 15 may be taken to be one of the ordinary forms of bunters, and P' the ordinary pin therefor. When it is desired to use the link N in combination with the pawls L for holding the cars together, the pawls L will be provided, 20 their back ends being pivoted in the spaces H by the pivot-bolts K. After the cars have been brought together and the pawls L have assumed the position shown in Fig. 3, or by dotted lines in Fig. 1, (the cars being stationary,) the pawls may be raised to a vertical position, as shown in Figs. 1 and 2, when the link N and pins P may be put in place, after 25 which the pawls may be returned to the position shown in Fig. 3.

35 If the link N is made with extra length beyond the length that is required for putting the pins P in place, as shown in Figs. 2 and 3, the link will only come into action in holding the cars together after the pawls have "given out," or are not employed for holding the cars together, in which case the link N forms only a second coupling in case of any derangement of the said pawls L; but if the links N are made a corresponding fit or length to the pins P that 40 the pawls L are to the bridge-pieces I', the strain to draw the cars apart will be jointly borne by the one pawl L and link N in combination.

45 What I claim, and wish to secure by Letters Patent, is as follows:

1. As an improved article of manufacture or construction, a bunter-body having extensions

and bridge-pieces, as described, said bridge-pieces being provided with holes for the introduction of the coupling-pin, and with a space 55 between them for the coupling-link, said space for the link being situated (as shown and described) in relation to the body of the bunter so that the link may be placed therein from the back thereof, the whole substantially as 60 described and shown.

2. As an improved article of manufacture or construction, a bunter having extensions and bridge-pieces, said bridge-pieces being provided with holes and counterbore for the reception of the coupling-pin and head thereof, and also provided with a space between them for the reception of the coupling-link, the said space for the link being relatively so situated (as shown and described) that the said link can 70 be placed therein from the back thereof; furthermore, the said bunter being provided with a recess or opening, H, and pivot K, passing through the one end of the pawl and attaching the pawl thereby, and with said pawl, the 75 whole substantially as described and shown.

3. The combination, in car-couplings, of a bunter-body, E, having extensions F, and bridge-pieces I', provided with holes O, and having space M, situated (as described and 80 shown) relatively so that the link N may be placed therein from the back thereof, the said bunter having the said parts, with another bunter similarly constructed, and with pins P and link N, the whole substantially as 85 described and shown.

4. The combination, in car-couplings, of the bunter-body E, extensions F, and bridge-pieces I, arranged to form the spaces G, H, and M, and the bridge-pieces I' being furthermore 90 provided with the holes O and counterbore R, the said space M being relatively so situated to the body of the bunter that the link N may be passed and placed therein from the back thereof, pawl L, pivot-bolt K, by which the said 95 pawl is attached and pivoted in the space H, one bunter having the said parts with another bunter similarly constructed, and with coupling-pins P and link N, the whole substantially as described and shown.
